Primary Examiner — Ramzi Almatrahi*(74) Attorney, Agent, or Firm* — Sheppard, Mullin, Richter & Hampton LLP; Hector A. Agdeppa; Daniel N. Yannuzzi(57) **CLAIM**

The ornamental design for a wireless radio unit, as shown and described.

DESCRIPTION

FIG. 1 is a top, front and left side perspective view of a wireless radio unit;

FIG. 2 is a top plan view thereof;

FIG. 3 is a bottom plan view thereof;

FIG. 4 is a right side elevation view thereof;

FIG. 5 is a left side elevation view thereof;

FIG. 6 is front elevation view thereof; and,

FIG. 7 is a rear elevation view thereof.

The broken lines depict portions of the wireless radio unit in which the design is embodied that form no part of the claimed design.
